R. J. WELLS.

JOINT REST FOR RAILWAY RAILS.

APPLICATION FILED SEPT. 16, 1918.

1,413,084.

Patented Apr. 18, 1922.

UNITED STATES PATENT OFFICE.

RALPH J. WELLS, OF DAYTON, OHIO.

JOINT REST FOR RAILWAY RAILS.

1,413,084.

Specification of Letters Patent. Patented Apr. 18, 1922.

Application filed September 16, 1918. Serial No. 254,203.

To all whom it may concern:

Be it known that I, RALPH J. WELLS, a citizen of the United States, residing at Dayton, in the county of Montgomery and State of Ohio, have invented certain new and useful Improvements in Joint Rests for Railway Rails, of which the following is a specification.

My invention relates to railway track construction and more particularly to a new and novel form of rail joint rest or seat for supporting the adjacent ends of succeeding rails.

The object of the invention is to simplify the construction of such devices whereby they will not only be cheapened in construction, but will be more efficient in use, easily installed in existing track as well as in new track constructions, of maximum strength, safe in operation and unlikely to get out of repair.

While the subject matter hereof is designed particularly as a repair part it is also useful in original installations. It is the common experience that with usage the rail ends are inclined to work loose and to unduly give or yield, especially under the impact of heavy traffic. The device herein described is in no sense a tie since it is intended for installation under but one side of the track. It will be understood that the rail joints in the respective sides of the track are usually offset and seldom or never come opposite each other. Hence the necessity for a joint rest or chair occurs at different points in the respective sides of the track.

Inasmuch as there is usually a jar or jolt as a car passes from one rail to another causing more or less noise and deterioration of the trackage, a further object of the invention is to so cushion the rail joint as to take up the jar or jolt and deaden the noise, and to provide a degree of resiliency which will reduce wear of equipment and increase the ease and comfort of riding.

With the above primary and other incidental objects in view as will more fully appear in the specification, the invention consists of the features of construction, the parts and combinations thereof and the mode of operation or their equivalents as herein-after described and set forth in the claims.

Referring to the drawings, Fig. 1 is a per-

spective view of an installation of the joint rest or chair forming the subject matter hereof. Fig. 2 is a side elevation partly broken away thereof. Fig. 3 is a perspective view of the rest or chair.

Like parts are indicated by similar characters of reference throughout the several views.

In the drawing, 1-1 are the rails of the track, of which 2 is the cross tie, while 3 represents the street paving which need be torn up only adjacent to one rail in order to install the rest or chair hereafter described.

The chair or rest comprises an elongated pan or receptacle 4 of sheet metal but which may be of fiber, composition, or other suitable material adapted to retain its shape while being embedded in the concrete filling of the road bed. Fitted within the pan 4 is a block 5 of wood or like material which rests upon a cushion 6 of asphaltum or other resilient material. In the event that asphaltum or other semifluid material is employed the wood block 5 is proportioned sufficiently accurate in relation with the interior dimensions of the pan or receptacle 4 to form a closure therefor and prevent the oozing of the cushion material upwardly when softened by summer heat and subjected to heavy traffic pressure. It has been found in practice that workmen are sometimes inclined to draw the attachment bolts hereafter mentioned so tight as to compress the cushion material and displace it from the pan while installing the device. To prevent this difficulty small sticks 7 of soft wood or like material which will temporarily withstand the pressure but which will quickly yield under actual usage are placed in spaced relation beneath the block 5 within the pan 4 and embedded in the cushion material 6.

Positioned transversely beneath the pan or receptacle 4 and extending laterally there beyond in both directions are stay arms or outrigger arms 8. These arms afford a wider bearing for the rest and prevent it tipping or tilting while in use. The terminal arms 8 are preferably angle bars while the intermediate arms are flat as shown. This however is not an essential feature. These arms may be of any convenient and suitable shape, and may be proportioned according to the strain to which the device will be subjected. Located on top of the block

5 is a plurality of surface plates 9. These plates comprise two terminal strips transversely arranged and a main plate intermediate the terminal strips. However it is 5 obvious that a single plate covering the entire block or such portion thereof as is necessary to withstand the shock and wear, may be employed.

Extending through the stay arms 8, the 10 pan 4, block 5 and surface plates 9 is a series of clamp bolts 10. These bolts carry clamp- ing heads 11 above the surface plates which engage with the base flanges of the rails. By means of the bolts 10 the rail ends are 15 firmly clamped upon the rest or chair.

In applying the device, a hole is ex- 10 cavated beneath the rail joint to be supported. This hole is under one side of the track only. The rest or chair is then clamped upon the 20 rail base by means of the clamp heads 11 and bolts 10, and is thus held suspended.

Gravel or preferably concrete grouting is 25 then tamped beneath the rest or chair until the rail is firmly supported at grade. The track is then preferably, though not neces- sarily left in this condition for a limited time while traffic passes over the rails. If it is found that the rest is not firmly bedded or that it is inclined to yield to an abnormal 30 extent, more gravel or grouting is tamped under until sufficient foundation is afforded.

The opening is then filled with grouting or 35 concrete covering and embedding the lateral arms 8 and firmly fixing the rest in place. The paving material is then relaid in the usual manner.

The inserts 7 afford only a temporary re- 40 sistance to prevent the workmen placing excessive pressure on the cushion material 6.

These inserts however disintegrate or 45 gradually give way allowing the block to be supported entirely upon the resilient cushion. In the event that the workmen may be trusted to not tighten the clamp bolts excessively, the inserts 7 are omitted. After once being embedded in the road bed 50 the concrete filling conforms to the block 5 above the edge of the pan 4 thereby preventing any displacement of material due to pressure of traffic passing over the rails.

From the above description it will be ap- 55 parent that there is thus provided a device of the character described, possessing the particular features of advantage before enumerated as desirable, but which, obvi- 60 ously, is susceptible of modification in its form, proportions, detail construction or arrangement of parts, without departing from the principle involved or sacrificing any of its advantages.

While in order to comply with the statute, 65 the invention has been described in language more or less specific as to certain structural features, it is to be understood that the in- vention is not limited to the specific details

shown, but that the means and construction herein shown and described, comprises but one of several modes of putting the invention into effect, and the invention is therefore claimed in any of its forms or modifications within the legitimate scope of the appended claims.

Having thus described my invention, I claim:

1. A support for railway rails, comprising 75 a single disconnected container, independent of the railway cross tie, a resilient cushion therein, a supporting block resting upon the cushion, and means for attaching the rails to said block.

2. A rest for railway rails comprising a 80 block on which the rails rest, and a plu- rality of cross arms connected to the block and projecting laterally in opposite direc- tions beyond the block transversely in rela- 85 tion with the supported rails, substantially as specified.

3. A support for railway rails comprising 90 a single socket member, a supporting block therein upon which the rails rest, a resilient cushion beneath said block and within said socket member, and outrigger arms extend- 95 ing transversely in relation with the sup- ported rails, adapted to prevent the tilting of the structure in the road bed.

4. A support for railway rails, a support- 100 ing block, a resilient cushion on which the block rests and means for temporarily sup- porting the block independent of the resil- ent cushion, substantially as specified.

5. A support for railway rails comprising 105 a supporting block, a resilient cushion on which the block rests, and non-yielding tem- porary supports for said block embedded in said resilient cushion, substantially as specified.

6. A support for railway rails comprising 110 a pan, a resilient cushion therein, a support- ing block resting on the cushion, transverse stay arms extending beneath said pan and project- 115 ing laterally therebeyond, and clamp bolts extending through the block, the pan and the stay arms adapted to attach the supported rails to said block.

7. A support for railway rails comprising 115 a resilient body, a bearing member over- lying said body on which the rails rest, stay arms transversely arranged in relation with the rails extending in opposite directions from the resilient body, and means for at- 120 taching the rails thereto, substantially as specified.

8. A rest for railway rails comprising a 125 single receptacle positioned beneath the rails to be supported and independent of the cross ties, a body of resilient material therein, a sleeper block forming a closure for the re- ceptacle, said block resting upon the resil- ent body and supporting the rail.

9. A rest for railway rails comprising a 130

receptacle positioned in the road bed independent of the cross ties, a quantity of asphaltum within said receptacle, a wooden block fitted within the receptacle forming a closure to prevent the escape of asphaltum when subjected to pressure, said block forming a rest for the rail.

In testimony whereof, I have hereunto set my hand this 9th day of September A. D. 1918.

RALPH J. WELLS.
